WILLIAM J. JOHNSON, OF NEW ORLEANS, LOUISIANA.

Letters Patent No. 88,178, dated March 23, 1869.

IMPROVED LOCOMOTIVE DRIVE-WHEEL.

The Schedule referred to in these Letters Patent and making part of the same.

To all whom it may concern:

Be it known that I, WILLIAM J. JOHNSON, of the city of New Orleans, in the parish of Orleans, and State of Louisiana, have invented a new and useful Improvement in Locomotive-Engines; and I do hereby declare that the following is a full and exact description thereof, reference being had to the accompanying drawings, which form a portion of this specification—

Figure 1 being a top view;

Figure 2, a side view;

Figure 3, a longitudinal partial section, in the line xx of fig. 1; and

Figure 4, a transverse partial section, in the line yy of fig. 1.

Similar letters indicate corresponding parts in each of the drawings.

My improvement in locomotive-engines consists, first and principally, in such an arrangement of parts as enables the driving-wheels thereof to be considerably enlarged in diameter, whilst at the same time it enables the centre of gravity of the machine to be brought considerably nearer to the track than can be accomplished in the construction of locomotive-engines by any other known practical method.

The said desirable results are accomplished by means of an arrangement of the running gear of the engine, which enables the principal portion or the whole of the weight of the engine to be borne upon the axles of small car-wheels CO , which rest and run upon the inner periphery of the rims of the driving-wheels AA , whilst the latter rest upon and travel over the rails in the usual manner. The said driving-wheels AA are kept upon the railway-track by means of the usual flanges. The smaller bearing-wheels CO are kept in their proper positions within the driving-wheels by means of suitable flanges.

The only burden carried upon the axles ee of the driving-wheels is a rectangular frame, $g g g g, hh, ii$, which is only of sufficient weight and strength to preserve the parallelism of said axles.

If a locomotive be supplied with only one pair of driving-wheels, the bearings of the axle thereof must be arranged and secured in such a manner as will insure at all times the proper position of said axle relatively to the frame of the locomotive and its several supporting-wheels.

The main frame of the locomotive, which receives the boiler and the furnace, may be of the usual shape, or any other shape that may in practice be found to be preferable.

In the accompanying drawings, the said frame is represented as being composed of the longitudinal side-plates KK , the end-plates LL , and the transverse connecting-plates nn .

The combination of said frame with the axles ff of the bearing-wheels CO , may be effected by the employment of appropriate springs and journal-boxes, in any well-known or usual manner.

The steam-cylinders, employed for transmitting power to the driving-wheels, may be rigidly secured to the frame of the locomotive, or may be sustained in such a manner as to oscillate on central trunnions.

In the accompanying drawings, the steam-cylinders OO are represented as being supported on trunnions, between vertical supporters pp , and as communicating power and motion to the driving-wheels AA , through the medium of short double cranks, qq , the longer cranks, rr , and the side coupling-bars SS .

The enlarged driving-wheels in my improved locomotive-engines will probably make it expedient to employ cranks of longer radius for communicating power to said wheels. This can be effected in the manner represented in the accompanying drawings, or steam-cylinders having a longer stroke of piston may be employed, and the piston-rods of said cylinders be connected to the driving-wheels by means of the usual or any other sliding and coupling-apparatus.

The advantages that will result from the lowering of the centre of gravity in locomotive-engines are too numerous and too palpable to require explanation or elaboration. The bringing of the principal portion, or the whole of the weight of the locomotive, to bear directly upon the inner periphery of the rims of the driving-wheels, must add greatly to the stability and steadiness of motion of the locomotive, and consequently enable it to be safely run at a much higher velocity than it would be safe to run any locomotive of the usual construction.

In the construction of my improved locomotive-engine, I do not intend to restrict myself to precise proportions of parts, or details of construction, as the same may be considerably varied without departing from the nature and spirit of my invention.

Having thus fully described my improved locomotive-engine,

What I claim therein as my invention, and desire to secure by Letters Patent, is—

1. The arrangement of certain of the parts thereof, by which a portion or the whole of the weight of said engine, is borne upon the axles of small car-wheels, which rest and run upon the inner periphery of the rims of the driving-wheels, substantially in the manner and for the respective purposes herein set forth.

2. When the principal portion, or the whole of the weight of a locomotive-engine, is made to bear upon the axles of car-wheels which rest and run upon the inner periphery of the rims of the driving-wheels thereof, I also claim the combination of the steam-cylinders OO with said driving-wheels, through the medium of the short cranks qq , the longer cranks rr , and the side coupling-bars SS , substantially in the manner herein set forth.

W. J. JOHNSON.
